WALL MOLD FORM

Stanley M. Pontiere, Philadelphia, Pa.

Application August 5, 1946, Serial No. 688,525

3 Claims. (Cl. 25—131)

1

This invention relates to devices for use in constructing molds for plastic walls to be built in situ.

An object of the invention is the provision of a wall mold construction in which vertical bars are secured removably to bolts embedded in the foundation of a building; said bolts also maintaining in place form board retainers that are provided with ribs for receiving and spacing the form boards between which the plastic materials are poured or tamped, said form boards being readily removable after the materials have set.

Another object of the invention is the provision of a wall mold construction in which a plurality of vertical bars and transverse bars which have spacing ribs are coordinated on a foundation of a building for removably holding a plurality of form boards to provide spaces for receiving plastic materials to form either a single wall or spaced double walls, the transverse bars being embedded in the finished walls while the vertical bars and form boards being removable for use in constructing progressive elevated courses of the wall, means being embedded in the foundation for removably retaining the vertical bars in operative positions.

A further object of the invention is the provision of a wall mold construction in which transverse bars are bolted to a previously formed foundation with vertical bars having lateral flanges at the opposite ends thereof, one of the flanges of each vertical bar being held in place by one of the bolts so that ribs on the transverse bars will cooperate with the vertical bars for retaining form boards in position to provide spaces into which plastic materials are poured or tamped, the other flanges on the vertical bars furnishing supports for additional vertical bars and transverse bars to retain elevated form boards in place for applying a succeeding course of plastic materials to the preceding course, the transverse bars remaining embedded in the plastic materials to tie parallel spaced walls together, the form boards and vertical bars being removable.

The invention consists in the novel construction, arrangement and combinations of parts hereinafter more particularly described and claimed.

In the drawings,

Figure 1 is a view in perspective of the top of a foundation showing bolts embedded therein for receiving the perforated ends of ribbed transverse bars.

Figure 2 is a view in perspective of a section

2

of a foundation showing transversely disposed bars and vertical form board-retaining bars held in the foundation by bolts embedded in said foundation and disclosing the second stage in the erection of the mold.

Figure 3 is a view in perspective of the section of the foundation shown in Figure 2 with form boards held in place by the transverse bars and vertical bars and disclosing the third stage in the erection of the mold.

Figure 4 is a view in perspective of the section of the foundation shown in Figures 1 to 3 inclusive disclosing the addition of transverse bars at the upper edges of the form boards for retaining the boards in place while the plastic materials are being poured.

Figure 5 is a view in perspective of a section of a foundation with set spaced walls rising therefrom showing the last stage in the formation of a first course and disclosing the inner form boards in the process of removal, and

Figure 6 is a view in perspective of the completed first course shown in Figure 5 and disclosing additional transverse bars and vertical bars secured to top flanges of the vertical bars employed in the first course for holding elevated form boards to provide a mold for a succeeding course of plastic materials.

Referring more particularly to Figure 1, 10 designates the usual foundation of plastic materials which are set in a channel or trench dug in the ground. Pairs of bolts 11 are placed in the foundation before the plastic materials have set. The distance between each pair of bolts transversely of the foundation is determined by passages in the ends of transverse bars 12, while the distance between the pairs of bolts lengthwise of the foundation is determined by the length of form boards 13 and 14.

Each transverse bar 12 has an upstanding short rib 15 adjacent each end of said bar, a centrally disposed rib 16 and a pair of ribs 17 at each side of the rib 16. The number and spacing of the ribs will depend upon the number and the positions of form boards required for building a particular type of wall.

A vertical bar or form board support 20 has a lateral flange 21 at the lower end and said flange is provided with a perforation to receive one of the bolts 11. A nut 22 secures said flange to an end of a transverse bar 12 so that the bars 20 will be held in vertical positions. The perforations in the flanges 21 are so placed that the inner faces of the bars 20 will be spaced a sufficient distance from the outer ribs 15 that the lower

edges of the form boards 13 will be received neatly between the ribs 15 and the bars 20. The upper end of each vertical bar 20 has a lateral flange 23 provided with a perforation 24 for a purpose which will be presently explained.

The inner form boards 14 have the lower edges received between the central rib 16 and an adjacent rib 17 so that the inner boards 14 will provide an air space between the set vertical walls 25 and 26 (Figures 5 and 6).

After the form boards are placed in position as shown in Figure 3 upper transverse bars 30 are placed on the tops of said boards with perforations in the ends of said bars aligning with the perforations 24 in the upper flanges 23 at the tops of the vertical bars 20. The bars 30 are then secured to the flanges 23 by bolts 31 and nuts 32 (Figure 4).

A rib 33 is located on the upper surface of the bar 30 adjacent each end thereof and pairs of ribs 34 and 35 are disposed between the end ribs 33. The lower edge of an outer form board (not shown) is adapted to be received between an outer rib 33 and an elevated vertical bar 36 secured by the bolts 31 to the ends of the transverse bars 30 (Figure 6). The pairs of ribs 34 and 35 are adapted to receive the lower edges of a pair of inner form boards (not shown).

The under face of each transverse bar, adjacent each end, has a depending rib 40 which bears against the inner upper faces of the form boards 13. The under face of each transverse bar 30 has also pairs of depending ribs 41 which receive the upper edges of the inner form boards 14 (Figure 4).

The form boards 13 and 14 are cut the proper size from plywood composed of three layers. These form boards are treated with an oil to render them impervious to moisture so that they will not contract or expand in use or in storage after having been subjected to the wet plastics.

In erecting walls with the molds of knock-down construction, the foundation 10 is laid first and the pairs of bolts 11 are forced into the wet plastic. The transverse bars 12 are applied with the perforations in the ends of said bars receiving said bolts. The vertical form supporting bars are positioned as shown in Figure 2 and the nuts 22 are screwed up tight on the flanges 21 after the cement has set.

The inner form boards 14 are placed upon the transverse bars 12 with the lower edges seated on the transverse bars on opposite sides of the centrally disposed rib 16. The outer form boards 13 are next positioned with the lower edges seated between the end ribs 15 and the vertical bars 20, the outer faces of the form boards being in contact with the inner faces of said vertical bars as shown in Figure 3.

Figure 4 discloses the application of the top transverse bars 30 to the upper flanges 23 of the vertical bars 20 where bolts 31 and nuts 32 secure the transverse bars to said flanges. When the transverse bars 30 are laid upon the flanges 23, the pairs of depending ribs 41 are fitted over the upper edges of the form boards 14 while the end ribs 40 engage the inner faces of the upper ends of the form boards 13 forcing the boards in contact with the vertical bars 20.

The plastic materials are ready to be poured into the spaces between the pairs of form boards 13 and 14. When the materials have set, the upper transverse bars 30 are removed after which the inner form boards 13 are withdrawn (Figure 5).

The next course can only be applied after the transverse bars are returned and the succeeding uprights or form supporting bars 36 are secured in place by the bolts 31 and nuts 32. The removed form boards 14 are then seated in the pins of upstanding ribs 34 and 35 while a pair of additional outer form boards are so placed that the lower edges thereof will be seated between the upstanding end ribs 33 and the adjacently disposed vertical bars 36. A third group of transverse bars are secured to the upper end of the vertical bars 36 with corresponding depending ribs to engage and hold the upper ends of the form boards in place.

Since all of the additional transverse bars and vertical bars required to raise the walls to the proper height are identical with the transverse bars 30 and the vertical bars 20 no further disclosure need be set forth. However, when the extreme height of the wall has been reached transverse bars which are identical with those shown at 12 in Figure 1 and Figure 2 are employed although said bars are reversed so that the fins or ribs will be in pending positions while the upper surfaces will be flat.

When the walls have been completed the vertical bars 20 and 36 together with any succeeding bars will be removed as will be all the outer mold boards 13 which have been returned in place during the progressive building stages of the walls.

When pairs of spaced walls 25 and 26 are formed as shown in Figures 5 and 6, all the transverse bars will remain embedded in the set plastic materials and will act as the rods between said walls. On the other hand, when single walls are constructed the inner form boards will be eliminated as will be the upstanding and depending ribs which are required for positioning said inner form boards.

The projecting ends of the transverse bars may be readily broken off since the transverse bars are made of cast iron.

I claim:

1. A mold form adapted to be placed longitudinally on the foundation of a wall, said wall having spaced threaded bolts rising therefrom in pairs, spaced transverse bars having perforations at the ends thereof to receive the bolts, vertical bars having perforated lateral flanges at the opposite ends thereof, the lower perforated flanges on the vertical bars receiving one of the bolts, nuts on the bolts securing the lower flanges to the ends of the transverse bars, said transverse bars having upstanding ribs to receive form boards, and ribs cooperating with the vertical bars to receive outwardly positioned form boards therebetween and transverse bars over the upper edges of the form boards connected with the upper flanges of the vertical bars.

2. A mold form adapted to be placed longitudinally on the foundation of a wall, said wall having spaced threaded bolts rising therefrom in pairs, spaced transverse bars having perforations at the ends thereof to receive the bolts, vertical bars having perforated flanges at the opposite ends thereof, the lower perforated flanges on the vertical bars receiving one of the bolts and being in engagement with the ends of the transverse bars, nuts on the bolts securing the flanges to the ends of the transverse bars, said transverse bars having upstanding ribs, form boards positioned between said ribs, form boards disposed between said vertical bars and an adjacent rib 75 of the transverse bars, transverse bars connected

to the upper flanges of the vertical bars, and ribs depending from the last-mentioned bars and engaging the upper edges of the form boards and cooperating with the first mentioned ribs and vertical bars for retaining the form boards in spaced parallel relation.

3. A mold form of knock-down construction for building walls of plastic materials in which a succeeding course is laid upon a preceding course comprising a plurality of spaced bars resting upon the upper surface of a finished course, vertical bars rising from each end of the transverse bars, outer form boards disposed against the inner surface of the vertical bars, means removably securing the vertical bars on the transverse bars, upper transverse bars connecting the upper ends of the vertical bars together, means projecting from the first mentioned transverse bars and the upper transverse bars for retaining spaced form boards disposed between said means and retaining the form boards in vertical planes between the first mentioned form boards, a second series of vertical bars having the lower end connected to the ends

of the upper transverse bars and transverse bars connecting together the upper ends of the last-mentioned vertical bars to provide supports for additional form boards above the first-mentioned form boards and in vertical alinement with said first form boards.

STANLEY M. PONTIERE.
